ATTORNEY

UNITED STATES PATENT OFFICE.

ARNOLD ZUKOR, OF NEW YORK, N. Y.

BURGLAR ALARM.

Application filed September 5, 1922. Serial No. 586,161.

To all whom it may concern:

Be it known that I, ARNOLD ZUKOR, a citizen of the United States, and resident of the city of New York, in the county of New York and State of New York, have invented certain new and useful Improvements in Burglar Alarms, of which the following is a specification.

The present invention relates to improvements in burglar alarms.

One of the objects of the invention is to provide a device of this character which is simple in construction, efficient in operation and capable of manufacture on a commercial scale, or in other words one which is not so difficult to make as to be beyond the reasonable cost of such a contrivance.

Another object of the invention is to produce a device of this type which may be readily placed in position to protect a door, it being actuated by the door when the same is attempted to be moved toward open position.

With these and other objects in view, which will appear as the nature of the invention is better understood, the same consists in the combination, arrangement and construction of parts hereinafter fully described, pointed out in the appended claim and illustrated in the accompanying drawings, it being understood that many changes may be made in the size and proportion of the several parts and minor details of construction without departing from the spirit or sacrificing any of the advantages of the invention.

One of the many possible embodiments of invention are illustrated in the accompanying drawings, in which:—

Fig. 1 is a side elevation of the improved alarm, shown applied to a door; Fig. 2 is a front elevation, on a larger scale, of a portion of the alarm shown in Fig. 1; Fig. 3 is a sectional view of the detail shown in Fig. 2; Fig. 4 is a front elevation of a mechanism for detachably fastening the alarm shown in Fig. 1 to a door; Fig. 5 is similar elevation of the said fastening device, the elements being shown in other positions; and Fig. 6 is a section taken on line 6—6 of Fig. 5.

In the drawings, the burglar alarm is attached to the inner face of a door 41 and rests upon the floor of the room. In this instance, there is pivoted at 42 a bar 43 to an element 44, the latter being secured by screws, or otherwise, to the door. The pivot pin 45 on the bar 43 extends through a sta-

tionary ear 46 and a movable ear 47 on a base plate 48, the base plate being fixed to the door. A set screw 49 serves to hold the movable ear in the desired position relative to the stationary ear 46, preventing a disengagement of the bar 43 from the element 44. Upon the outer end of the bar 43 is mounted a piston 50, slidably in a cylinder 51 on a bar 52, the lower free end of which is pointed, as shown at 53, it being an engagement with a corrugated plate 54, that is fixed to the floor adjacent to the door. A spring 55 is disposed within the cylinder 51, its purpose being to hold the bar 43 in its elevated position. To the cylinder is attached a bell 38, preferably, a rotatable bell, containing a suitable mechanism, such as a hammer and actuating mechanism therefor, whereby, when the bell is released and allowed to be revolved by the usual spring motor, the bell is sounded. With the escapement of the motor of this bell co-operates a stop 40, which is disposed in operative relation to a pin 56, that is attached to the piston 50, extending through a longitudinal slot 57 in the said cylinder.

The operation of this device is as follows:—When the door is being opened, the piston 50 is depressed against the action of the spring 55, the pin 56 being brought into abutment with the stop 40, forcing the same downwards and releasing the escapement of the spring motor. Inasmuch as the lower end of the bar 52 is seated in one of the corrugations of the plate 54, the door can be opened to a certain extent only. The device acts thus, besides being a burglar alarm, as a safety device for the door.

What I claim is:

The combination with a door, of a bar attached thereto at its upper end and carrying at its lower end a piston, a cylinder in which said piston is slidably arranged, a second bar fixed to said cylinder for engagement with the floor adjacent the door, the longitudinal axes of said bars forming a continuation of one another, a bell carried by said cylinder, a pin mounted upon said piston and adapted, when moved, to operate said bell, and a spring within said cylinder bearing on said piston for normally holding said pin disengaged from said bell.

Signed at New York, in the county of New York and State of New York, this 29th day of August, A. D. 1922.

ARNOLD ZUKOR.
